UNITED STATES PATENT OFFICE.

WILLIAM A. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,149,659.

Specification of Letters Patent. Patented Aug. 10, 1915.

Application filed June 3, 1908. Serial No. 436,330.

To all whom it may concern:

Be it known that I, WILLIAM A. LORENZ, a citizen of the United States, residing at Hartford, in the county of Hartford and 5 State of Connecticut, have invented certain new and useful Improvements in Type-Writing Machines, of which the following is a full, clear, and exact description, such as will enable others skilled in the art to 10 to which it appertains to make and use the same.

This invention relates to typewriting machines and more particularly to that class of machines wherein endwise sliding type 15 bars are employed.

One of the objects of the present invention is to provide improved means for guiding the type bars in their movements toward and from the platen.

20 Another object is to provide improvements generally in the actuating mechanism for endwise movable type bars, whereby the printing mechanism may be operated with a minimum amount of friction and the various operative parts of the actuating mechanism may be kept in perfect alinement.

Other objects will be in part obvious and in part pointed out hereinafter.

The invention accordingly consists in the 30 features of construction, combinations of elements and arrangement of parts which will be exemplified in the construction hereinafter set forth, and the scope of the application of which will be indicated in the 35 following claims.

In the accompanying drawing, wherein are illustrated two of the various possible embodiments of my invention, Figure 1 is a vertical sectional view taken from front to 40 rear of a typewriting machine, the mechanism constituting the invention being shown in elevation; Fig. 2 is a similar view showing the position of the parts when the type bar is projected to the printing point of the platen; Fig. 3 is a top plan view of the 45 mechanism shown in Figs. 1 and 2; Fig. 4 is a view similar to Fig. 1, but showing certain features of the invention in modified form; Fig. 5 is a top plan view showing a 50 portion of the bed upon which the type bars rest and the embodiment of the type bar guiding means illustrated in Fig. 4; Fig. 6 is a rear view of a portion of the guiding mechanism for the type bars disclosed in

this embodiment of my invention; Fig. 7 55 is an enlarged view in plan of a portion of the actuating mechanism for the type bars; and Fig. 8 is an end view thereof.

Similar reference characters refer to similar parts throughout the several figures of 60 the drawings.

Referring now to the drawings, 1 denotes a portion of the framework of the machine, said framework supporting a bed 2 upon which the type bars rest and across which 65 they slide when they are projecting against the platen. Bed 2, in the present instance, is formed in two parts for convenience of assembly, the upper part being constituted by a plate 3 which is interposed in the im- 70 mediate support of the type bars. A plate 4 is supported in the framework of the machine above plate 3 and is engaged by the upper edges of the type bars. Plates 3 and 4, as will be seen, coöperate to guide the 75 type bars against vertical movements.

Referring now particularly to the embodiment of my invention illustrated in Figs. 1 to 3 inclusive, 5 and 6 indicate, respectively, guide pins which are extended upwardly 80 from plate 3, said guide pins being set therein. Guide pins 5 and 6, as will be noted, are arranged in two sets or series disposed one behind the other, each series being arcuately arranged, and between adjacent pins 85 of said series the type bars 7 are adapted to slide, as clearly shown in Fig. 3 of the drawings, the guide pins engaging the sides of the type bars adjacent their lower edges.

Extending downwardly from plate 4, in the 90 present instance, is another series of similar guide pins 8 between adjacent pins of which are received the type bars and which engage the sides of the type bars adjacent their upper edges. Each of the type bars 7, in the 95 present instance, is composed of an upper bar 9 and a lower bar 10 arranged in parallel relation, said bars being connected with their front and middle portions by cross-pieces 11 and 12, respectively, arranged at 100 right angles thereto and at their rear portions by an obliquely extending cross-piece 13. It has been found that by constructing a type bar in this manner the same will be stiffer and therefore better adapted to resist 105 deflection and curvature than have type bars of this character as heretofore constructed. The type head is shown at 14

and, in the present instance, carries three types which coöperate with a platen located in front of a paper roll, said latter parts being shown conventionally at 15 and 16, respectively. 17 denotes a cam block which is positioned upon a ledge 18 formed upon the front wall of the machine, said block being adjustably mounted thereon and held in fixed position by means of a clamp screw 20. 10 One of these blocks 17 is provided for supporting each of the several actuating mechanisms employed for projecting the type bars to an impression. Block 17 in its forward portion is bifurcated as shown, and swiveled 15 between the bifurcated portions 21 and 22 thereof is a member 23 provided with a cam groove 24. In order to strengthen member 23 and prevent the same from bending or buckling under the stress of writing, a 20 strengthening web is provided, as at 25, said web being formed integral with the member 23 and arranged adjacent the cam groove thereof. A double link 26 straddles this cam member and is pivotally attached thereto as at 27, the other end of said link straddling the type bar and being pivotally attached thereto at 28 intermediate the ends 25 of the middle cross-piece 11. At this point, it may be noted that between the ends of 30 the two series of guide pins 6 and 8 a space is provided to accommodate link 26 when the same is projected forward to carry the type bar to impression. 30 denotes a double bell-crank lever which straddles the bifurcated portion of block 17 and is pivoted thereto at 31. One arm of said lever is provided with a roller 32 which is adapted to traverse the cam groove of member 23 and the other arm of said lever is connected 35 with a link 33, which in turn is connected with the key levers (not shown). It will be understood that when the key levers are depressed link 33 will be caused to swing bell-crank lever 30 to the position shown in 40 Fig. 2 of the drawings, thereby oscillating the cam member 23 and projecting the type bar against the platen, link 26 being received between the ends of the guide members. 45

In Figs. 4 to 6 inclusive, I have provided 50 another form of guiding means for the type bars, which is constituted by toothed members or combs, two lower comb members 34 being let into the top plate 3 of the bed and the other comb member 35 being supported 55 by and depending from the top plate 4. These comb members are of arcuate form, as clearly shown in Fig. 5 of the drawings, and are preferably beveled off as shown in 60 Fig. 6. The type bars pass between adjacent teeth of the combs and are guided thereby at three points, as in the embodiment 65 of the invention first above described.

In each of the above-described embodiments, the cam member 23 and the bell-crank lever 30 are provided with portions

as at 37 and 38, respectively, which extend rearwardly behind their pivots. These portions aid in maintaining the various parts of the actuating mechanism in alinement.

It will accordingly be seen that I have 70 provided mechanism well adapted to attain, among others, all the ends and objects above enumerated in a simple yet efficient manner. The provision of the relatively short guide members for the type bars to the impression 75 point of the platen enables the link which connects the said type bars with the actuating mechanism to be connected at a point nearer the type heads than has been possible in prior constructions, inasmuch as 80 said link can pass freely between the ends of the guide members. This construction also avoids the necessity of swinging the link through so great an angle, as the same would have to be swung if it were connected 85 to the rear portion of the type bar. The construction of the actuating mechanism and the manner of mounting the same upon the cam block eliminates any chance of the several parts getting out of alinement, when 90 the same is operated to project the type bars against the platen.

As many changes could be made in the above construction and many apparently 95 widely different embodiments of this invention could be made without departing from the scope thereof, it is intended that all matter contained in the above description or shown in the accompanying drawings shall be interpreted as illustrative and not in a 100 limiting sense.

Having described my invention, what I claim as new and desire to secure by Letters Patent is:—

1. In a typewriting machine, the combination of a platen, an endwise sliding type bar, upper and lower guides for said type bar, and lateral guides for the same which extend in opposite directions from said first-named guides and engage the type bar at 105 either side thereof throughout its path of travel.

2. In a typewriting machine, the combination of a platen, an endwise sliding type bar, actuating mechanism therefor, a link 115 connecting the actuating mechanism with the type bar, upper and lower guides for said type bar, and lateral guides for the same, said guides being so disposed that said link may pass between the ends thereof 120 when the type bar is projected to printing position.

3. In a typewriting machine, the combination of a platen, an endwise sliding type bar, actuating mechanism therefor, a link 125 connecting the actuating mechanism with the type bar, and lateral guide members which extend upward and downward from said first-named guides, a space being provided between the ends of said last-named 130

guides in which said link is received when the type bar is thrust to impression.

4. In a typewriting machine, the combination of a platen, an endwise slidable type bar, a bed for supporting the same and across which it is adapted to slide, a plurality of relatively short guide members extending upwardly from the bed between which the type bar slides, a plate above said type bar, and a plurality of relatively short guide members extending downwardly from said plate between which said type bar slides, adapted to hold said bar in upright normal position.

15 5. In a typewriting machine, the combination of a platen, an endwise movable type bar, a bed upon which said type bar rests and upon which it slides in its movements toward and from the platen, a plate engaging the upper edge of the type bar, a plurality of pairs of guide pins extending upwardly from the bed and engaging the sides of the type bar near the lower edge thereof, and a pair of similar pins depending from said plate and engaging the side of the type bar near the upper edge thereof.

6. In a typewriting machine, the combination of a platen, an endwise slidable type bar, a bed upon which said type bar rests, and upon which it slides in its movements toward and from the platen, actuating mechanism for said type bar, a link connecting said actuating mechanism and the type bar, a plate engaging the upper edge of the type bar, a plurality of pairs of guide pins extending upwardly from said bed and engaging the sides of the type bar near the lower edges thereof, and a pair of similar guide pins depending from said plate and engaging the sides of the type bar near the upper edge thereof, a space being provided between the ends of said upper and lower guide pins for receiving said link when the type bar is projected toward the platen by

45 the actuating mechanism.

7. In a typewriting machine, the combination of a platen, an endwise movable type bar, actuating mechanism therefor, a link connecting the actuating mechanism and said type bar, a bed upon which the type bar slides in its movements toward and from the platen, two pairs of guide pins extending upwardly from the bed and engaging the opposite sides of the type bar near the lower edge thereof, a plate engaging the upper edge of the type bar, and a pair of pins depending from said plate and engaging the sides of said type bar near the upper edge thereof, a space being provided between the ends of said upper and lower guide pins for receiving said link when the type bar is projected toward the platen.

8. A type-bar comprising a pair of members arranged in parallel relation, cross- 65 pieces disposed at an angle to each other

connecting said members at their ends, and intermediate means at substantially the center of said type-bar, whereby the same is adapted to be connected with its actuating mechanism.

9. A type bar comprising a pair of members disposed in parallel relation and connected at their front, center and rear portions by cross members, the middle of said cross members being adapted to be connected with the actuating mechanism for the type bar.

10. In a type action, in combination, a type-bar, a block supported upon a relatively fixed portion of the framing of the machine, said block having a bifurcated portion, and an oscillatory cam member swiveled in the bifurcated portion of said block and having a portion thereof in front of its pivot when in actuated position adapted to fit said bifurcated portion and prevent a lateral movement of said cam member.

11. In a typewriting machine, the combination with slidable type bars, a bed upon which the type bars slide, a plate engaging the upper edge of said type bars and adapted to guide the same, and a plurality of guide members projecting upwardly from said bed and downwardly from said plate between which said type bars are received and which form lateral guiding means therefor, said guide members being arcuately disposed upon said bed and plate.

12. In a typewriting machine, the combination of a platen, endwise movable type bars and means for guiding said type bars in their movements from and to the platen, comprising a pair of spaced plates each of which engages the edges of the type bars, and guide members projecting from said plates, which engage the sides of the type bars adjacent their edges, said guide members being arcuately disposed upon said plate.

13. In a typewriting machine, the combination of a platen, an endwise movable type bar, a bed for supporting the type bar and upon which it slides in its movements toward and from the platen, a block supported upon a fixed portion of the framing of the machine, said block being provided with a bifurcated portion, a cam member swiveled in said bifurcated portion and having a portion thereof extended behind its pivot, said cam member being provided with a cam groove, a link connecting said cam member with said type bar, a bell-crank lever swiveled on the bifurcated portion of said block, and having a portion thereof extended behind its pivot, a roller carried by one arm of said bell-crank lever and adapted to traverse said cam groove, and a link adapted to connect the other arm of said bell-crank lever with a key lever.

14. In a typewriting machine, in combi-

nation, a type bar and actuating mechanism therefor including a toggle, one link of which is curved, means associated with said link to prevent flexing in its direction of curvature, and means to prevent a lateral movement of the toggle as it assumes extended position.

15. In a typewriting machine, the combination with the platen, of an endwise slide-
10 able type bar, a bed upon which said type bar slides, a plate engaging the top edge of the type bar and adapted to guide the same, a plurality of pointed members extending upwardly from the bed and engaging the
15 sides of the type bar adjacent the lower edge thereof, and a plurality of similarly formed members extending downwardly from said plate and engaging the sides of the type bar near the top edge thereof.

20 16. In a typewriting machine, the combination of a platen, an endwise movable type bar, a bed upon which said type bar rests and upon which it slides in its movements toward and from the platen, a plate
25 engaging the upper edge of the type bar, a plurality of pairs of bevel ended guide pins extending upwardly from the bed and en-

gaging the sides of the type bar near the lower edge thereof, and a pair of similarly formed pins depending from said plate and
30 engaging the sides of the type bar near the upper edge thereof.

17. In a typewriting machine, the combination of a platen, type bars, upper and lower guides for said type bars and lateral
35 guides for the same extending in opposite directions from said first-named guides and interposed between adjacent type bars.

18. In a typewriting machine, in combination, a paper carrier, a flat platen thereon, a plurality of type bars having a limited length of movement adapted to co-act with said platen, upper and lower guide members for said type bars, and means extending from said upper and lower guide members adapted to co-act with the sides of said type bars throughout their path of travel to prevent lateral movement thereof.

In testimony whereof I affix my signature, in the presence of two witnesses.

WILLIAM A. LORENZ.
